UNITED STATES PATENT OFFICE.

MATTHIAS BROCK, OF ROXBURY, AND LOUIS M. BROWN, OF BEVERLY, MASSACHUSETTS, ASSIGNORS TO UNITED SHOE MACHINERY COMPANY, OF PATERSON, NEW JERSEY, A CORPORATION OF NEW JERSEY.

MACHINE FOR FORMING UPPERS OF BOOTS AND SHOES.

1,170,405.

Specification of Letters Patent.

Patented Feb. 1, 1916.

Application filed February 9, 1914. Serial No. 817,544.

To all whom it may concern:

Be it known that we, MATTHIAS BROCK and LOUIS M. BROWN, citizens of the United States, residing at Roxbury, in the county of 5 Suffolk and Commonwealth of Massachusetts, and Beverly, in the county of Essex and Commonwealth of Massachusetts, respectively, have invented certain Improvements in Machines for Forming Uppers of 10 Boots and Shoes, of which the following description, in connection with the accompanying drawings, is a specification, like reference characters on the drawings indicating like parts in the several figures.

15 This invention relates to the shaping of the uppers of boots and shoes.

Although the invention is herein disclosed as embodied in a machine for use in the manufacture of that class of shoes commonly 20 known to the trade as "stitch-downs", in which the upper is provided with an out-turned flange to receive the stitches or other fastenings by which the upper is secured to the sole, it will be apparent that many 25 of the novel features of construction and principles of operation are applicable to the manufacture of shoes of other types.

According to a preferred practice in the manufacture of "stitch-down" shoes, the 30 upper before its attachment to the sole is subjected to a forming or molding operation in which the sole attaching flange is shaped to lie about the toe portion and the toe is given the shape desired for the finished shoe. A method of preparing an upper in this manner forms the subject-matter 35 of U. S. Letters Patent No. 947,895 granted on the application to Karl Engel, Feb. 1, 1910, and a machine by the use of which such 40 a method may be practised is disclosed in U. S. Letters Patent No. 998,682, granted on the application to Karl Engel, July 25, 1911. According to the practice disclosed in these patents, the marginal portion of the 45 upper blank at the toe end is first clamped between members that confine the margin during the toe forming operation and impart the pressure necessary to form the out-turned flange, and the unconfined portion of 50 the blank is then operated upon by a toe former that curves the blank to the shape of the toe of the finished shoe and is moved to cause the toe to project somewhat over the out-turned flange. It will be obvious

that in this toe forming operation, unless 55 the blank may be so adjusted as to provide the unconfined portion with the requisite fullness the clamped marginal portion will be subjected to strains to compensate for the excess of material required for the curved 60 shape of the toe, and in view of the further fact that some portions of the toe, as for example the abruptly curved end, require a relatively greater amount of material than other portions, the strains upon different 65 portions of the margin will differ both in direction and in degree. In order to avoid unduly straining or tearing the blank it is necessary, therefore, to provide for some redistribution or adjustment of the material to 70 meet the demands of the operation of the toe former. In the practice set forth in the patents above mentioned, accordingly, provision is made for suitable compensating movement of the flange portion of the blank 75 during the toe forming operation.

An object of this invention is to effect improvements in mechanism for forming or shaping shoe uppers.

A more particular object is to provide 80 mechanism of improved construction and mode of operation for imparting compensating movement to the material of the blank to meet the demands of the toe forming operation, so as to avoid danger of 85 cracking or tearing the material.

Contributing to the above and other ends, a feature of the invention resides in means for imparting to an upper blank, primarily at its marginal portion, movement in such 90 directions and to such extent as to effect the necessary relative adjustment of different portions of the material of the blank before the toe forming operation, so that during the latter operation the marginal portion of the blank will not be subjected to excessive strains and may be securely clamped and held from movement relative to the clamping means. With this arrangement there is no tendency in the toe forming operation for the material to be injured by reason of movement between and over the abrupt edges of the clamp members and the marginal portion of the blank may be subjected, irrespective of other considerations, 95 to the desired degree of pressure for forming a flange thereon.

Another feature of the invention resides

in the provision of means for imparting gathering movement to different portions of the blank in succession to effect the final required adjustment of the material. In the 5 preferred arrangement shown the material is gathered first at the toe end of the blank, and other portions of the blank at the margin are moved subsequently in the general direction of the toe end to effect a further gathering of the material.

10 Further features reside in the provision of mechanism of novel construction and arrangement for engaging and imparting to portions of an upper blank the movements required to distribute the material in accordance with the demands of the toe forming operation, and for forming a flange on the marginal portion of the blank, with suitable provisions for adjustment to vary 15 the width of the flange and to vary the amount of gathering movement imparted to portions of the blank.

15 These and other features of the invention, including certain details of construction and combinations of parts, will now be described with reference to the accompanying drawings and pointed out in the claims.

20 The invention is illustrated as embodied in a machine of the general type disclosed 30 in the pending application of Karl Engel and Louis M. Brown, Ser. No. 464,559, filed Nov. 27, 1908. The machine shown in said application comprises mechanism for shaping the toe and heel portions of upper 35 blanks, but only such portions of the complete machine as are directly related to the features of the present invention will be described herein. It should be understood also that the invention is not limited in its 40 application to this particular machine but is susceptible of various embodiments.

45 In the drawings, Figure 1 is a vertical section through a machine of the type above referred to, with the present invention embodied therein, Fig. 2 is a perspective view of a detached portion of the mechanism for operating upon the forepart of the upper, Fig. 3 is a plan view of the mechanism shown in Fig. 2, with portions broken away, 50 showing the parts in clamping position at the completion of the forming operation upon a blank, Fig. 4 illustrates in detail one of the gripping devices for the marginal portion of a blank and the means for moving the device to shift the position of the material, Fig. 5 shows one of the grippers detached, and Fig. 6 is a section on the line 6—6 of Fig. 3, illustrating the relative arrangement of the material shifting devices.

55 The complete machine, as described in the pending application above referred to, is 60 preferably provided with two upper forming mechanisms, one for forming the upper of a right shoe and the other for forming the upper of a left shoe. Since these mecha-

nisms both comprise the same parts, only that mechanism which is intended for use in forming the upper of a right shoe is shown and will be described herein in detail.

65 The upper forming mechanisms are inclined to the horizontal substantially on an angle of 45°, and as previously stated comprise means for forming or shaping the heel portion of the upper and means for shaping the toe portion of the upper, these means being arranged to operate in succession. The mechanism for operating upon the toe portion is carried by a slide 2 which is movable up and down the incline of the frame 4. This slide, it will be understood, is connected with means for operating upon the heel portion of the blank, and during the latter part of the heel forming operation is moved downwardly by means not illustrated herein in detail but fully described 80 in the pending application above mentioned, thereby bringing the mechanism for shaping the toe portion into position to receive the forepart of the upper from which the toe is to be formed.

90 The mechanism for operating upon the toe portion of the upper comprises two clamp members 6 and 8 constructed and arranged to clamp a marginal portion of the toe part of a width substantially equal to the desired width of the flange to be formed upon said part, the lower clamp member 6 being preferably stationary with respect to the upper clamp member and arranged to engage the unfinished side of the upper material or that side which will be located inside the finished shoe. Both clamp members are preferably formed with smooth material engaging faces, the unfinished side of the material being engaged, however, during the clamping operation by other members to be subsequently described and which operate in conjunction with the lower clamp member and are formed with roughened or toothed faces for engaging with greater security this 95 side of the material. The upper clamp member is formed as a plate cut back somewhat from its inner edge for a purpose hereinafter to be set forth, and is carried by a yoke 10 having ears 12 slidingly mounted upon headed rods 14 and pressed upwardly against the heads of these rods by springs 16.

100 The upper clamp member 8 is moved down into clamping relation to the lower clamp member 6, as set forth more fully in the above mentioned pending application, by the engagement with the yoke 10 of a clamp operating lever 18 which, it will be understood, is fulcrumed at one end upon the machine frame and is yieldingly connected at its other end to an operating rod 20. The lever and rod are loosely connected, and the rod is surrounded at its upper end by a spring 22 which bears upon a nut 24 105 110 115 120 125 130

and upon the lever and serves to uphold the rod with respect to the lever, this relative upward movement of the rod being limited by a nut 26 on the rod below the lever. The yoke 10 has formed upon its upper face a rib 28 which enters a corresponding groove in the lever 18 and serves to receive and equalize the pressure of the lever. The rod 20 is slotted at its lower end to receive a cam shaft 30, which is suitably rotated in the direction of the arrow shown on Fig. 1, and the rod carries a cam roll 32 which enters a groove 34 in a cam disk 36 on the shaft 30, the lower end of the rod being connected to a fulcrum link 38 by which its movements are partly guided.

After the marginal portion of the toe part of the upper has been clamped to form an out-turned flange, the unclamped portions are acted upon by a toe former 40 mounted upon a rod 42 adjustably carried by a slide 44 which is guided for movement longitudinally of the upper in guide grooves 46 in a slide 48 arranged to move at right angles to said direction of movement of the slide 44. The toe former 40 has two movements, one movement transverse to the clamping means or to the plane of the clamped portion of the upper and the other longitudinally of the clamping means and substantially parallel to the plane of said clamped portion. The first of these movements is effected by the movement of the slide 48, which carries a cam roll 50 that enters a cam groove 52 in a cam disk 54 on the cam shaft 30, the lower end of the slide being forked to embrace the cam shaft by which it is partly guided in its movements.

For moving the toe former in directions substantially parallel to the plane of the clamped portion of the upper there is provided a slide 56 which is carried by the slide 2 and is formed with an opening 45 through which the rod 42 moves in imparting to the toe former its movement transverse to the plane of the clamped portion of the upper. The slide 56 is adjustably connected by a rod 58 to a toggle actuated member 60, the adjustable connections between the rod and member comprising a threaded sleeve 62 on a shouldered portion of which the member 60 is confined by a nut 64, said sleeve being arranged to be turned by a gear 66 intermeshing with a second gear 68 upon a shaft 70 confined against longitudinal movement in a bearing 72 in an upstanding lug 74 on the slide 2.

Turning of the sleeve 62 alone serves to adjust the toe former 40 with respect to the clamp members 6 and 8. These clamp members, however, are carried upon a third slide 76 into an upstanding portion of which 65 the shaft 70 is threaded, so that when said

shaft is turned by the hand wheel 78, the slide 76 is adjusted upon the slide 2. The threads upon the shaft 70 are of the same pitch as those upon the rod 58, and the gears 66 and 68 have the same number of teeth, 70 so that when the shaft 70 and the sleeve 62 are turned together there will be no relative adjusting movement of the toe former 40 and the clamp members 6 and 8.

When it is desired to adjust the position 75 of the toe former with respect to the clamp members, the gear 68 may be disconnected from the shaft 70 and slid along said shaft out of engagement with the gear 66, whereby the sleeve 62 may be turned without turning the shaft 70. Variation of the limit of forward movement of the toe former longitudinally of the upper varies the bulge of the toe over its flange and at the same time varies the amount of longitudinal stretch 85 given to the upper during the toe forming operation, the heel portion of the upper being at this time clamped in the heel forming mechanism. Simultaneous adjustment of the slides 56 and 76 upon the slide 2 90 adapts the toe forming mechanism to operate upon shoes of different sizes.

The member 60 is pivotally connected to one link 80 of a toggle, the other link 82 of which is connected to the slide 2. The toggle is straightened and broken, to effect a forward movement of the toe former longitudinally of the upper during the toe forming operation and a backward movement respectively, by a link 84 connected at 100 one end to the knee joint of the toggle and at its other end to a fulcrum link 86 upon a bracket 88 on the slide 2, whereby the link 84 is caused to travel with the slide, the link 84 being provided at its joint with the fulcrum link 86 with a pin 90 which enters a slot 92 in an offset arm 94 of a toggle operating slide 96 forked at its lower end to embrace a cam shaft 98, which is suitably rotated in the direction of the arrow in unison with the cam shaft 30. The slide 96 is reciprocated to effect its toggle straightening and breaking operations by the engagement of a cam roll 100 on the slide with a cam groove 102 in a cam disk 104 of the cam 110 shaft 98. The slide 96 is suitably guided at its upper end by the frame. The amount of movement of the toe former 40 caused by the straightening of the toggle 80, 82 may be varied by turning the nut 64 upon the 120 sleeve 62 so as to provide lost motion between the member 60 and the sleeve.

As hereinbefore suggested, an important object of this invention is to provide improved means for effecting a suitable adjustment of the material of the blank to meet the demands of the toe forming operation and to avoid subjecting any portion of the blank to undue or excessive strains. For this purpose the upper clamp member 8 car- 125

ries upon its lower or clamping face a plurality of grippers comprising in the construction herein shown, pairs of jaws 106 and 108, of which the members 106 are provided with fulcrum pins 110 that pass through and are headed upon the upper side of the clamp member 8. The lower jaws 108 are pivoted transversely to the pins 110 and are so proportioned as to be normally 5 opened by gravity when the clamp member 8 is in its uppermost position. A pin 112 projecting from the jaw 106 and entering a slot in the jaw 108 serves to guide the jaw 108 in its closing and opening movements. 10 The fulcrum pins 110 thus serve to pivot both jaws of the gripping devices for swinging movement together about axes that extend transversely to the planes of the clamping faces of the members 6 and 8, and the 15 jaw 108 has in addition a closing and opening movement with respect to the jaw 106. The gripping devices, it will be seen, radiate outwardly from the blank engaging portion of the clamp member 8 and are arranged to engage the marginal portion of the blank before and during the clamping of the blank between the members 6 and 8. For gripping the lower or unfinished side of the material more effectively, the lower jaws 20 108 are provided with teeth at their material engaging ends, but the members 106 are preferably formed with smooth surfaces as shown to avoid injuring the material on its finished side. The jaws 106 of the two central gripping devices are connected together at their outer ends by a spring 114 that tends to swing apart the blank engaging ends of these devices, and the outer ends of the jaws 106 of those gripping devices which 25 40 are located nearer the sides of the clamp member are connected by springs 116 to pins 118 so as to swing the blank engaging ends of these devices outward and rearward toward the sides of the clamp member. The 45 springs thus serve to keep the blank engaging ends of the grippers normally separated as far as permitted by stop members which engage therewith and which will now be described. 50 The lower clamp member 6 is provided with a plurality of recesses 120 corresponding in number and relative locations to the gripping devices on the upper clamp member, and in these recesses are mounted bars 55 60 65 122 which are slotted to receive bolts 124 that are threaded into the member 6 and serve to secure the bars 122 in different positions of adjustment. These bars are formed at their inner ends with upstanding pins or projections 126 which are so located as to contact with the respective grippers and limit the swinging movement thereof under the influence of the springs 114 and 116. The pins 126 are formed with offset or cam 70 75 80 85 90 95 100 105 110 115 120 125 130 135 140 145 150 155 160 165 170 175 180 185 190 195 200 205 210 215 220 225 230 235 240 245 250 255 260 265 270 movement of the upper clamp member 8 to engage and close upwardly the lower jaws 108 and finally to impart movement to the grippers in opposition to the force of the springs 114 and 116 to gather in the marginal portion of the blank and effect the required compensating movement of different portions of the material before the margin is finally clamped between the members 6 and 8. 75

As illustrated in Fig. 6, the offsets 128 on the pins which are nearer the middle of the clamp member begin sufficiently high on the respective pins, relatively to the offsets on the pins that are more remote from the center of the clamp, to complete substantially the inward swinging movement of the two center gripping devices before the similar movement of the gripping devices which are nearer the sides of the clamp members. With this arrangement the gathering movement of the two center gripping devices is substantially completed before the other gripping jaws have closed upon the material, and is followed by the gathering movement toward the two center gripping devices of those devices which engage the material farther outwardly along the blank. Different portions of the blank are thus moved in succession to effect the final desired distribution of the material previous to the clamping and toe forming operations.

The pins 126 serve also as stops to gage the initial position of the margin of the blank and determine the width of flange 100 which will be formed between the members 6 and 8. On loosening the bolts 124, the bars 122 may be moved radially outward or inward to vary the width of this flange in accordance usually with the size of the blank which is to be operated upon, and the same adjustment will serve to vary proportionately the extent of gathering movement of the gripping devices according to the distances from the fulcrum pins 110 at which these devices are engaged by the offsets 128. The wider the flange, therefore, the greater the shifting movements which will be imparted to different portions of the blank.

The recesses 120 are of proper depth to receive the lower jaws 108 when the clamp members 6 and 8 are in clamping position and to leave the material engaging teeth on these jaws projecting slightly above the surface of the member 6 so as to assist the members 6 and 8 in holding the blank securely in position. The upper jaws 106, it will be understood, are so thin as not to interfere with the clamping of the material between the clamp members, and the recesses 120 are of sufficient width to accommodate variations in the extent of swinging movement of the grippers.

The side portions of the blank engaging part of the clamp member 6 are preferably 130 formed with offset or cam portions 128 which serve on the downward

provided with sockets inclined toward the rear of the corresponding part of the member 8, and in these sockets are mounted for endwise movement pins 130 the upper end surfaces of which are formed to lie in generally parallel relation to the clamping face of the member 6 and are roughened or toothed to engage the under surface of the material. The pins 130 are socketed to receive springs 132 and plungers 134, which are arranged to hold the pins normally projected a suitable distance from the face of the member 6. In view of the inclination of the pins 130, it will be understood that when the clamp member 8 has moved downwardly a sufficient distance to press the blank upon the projecting ends of the pins, further movement of the clamp member will serve to depress the pins in their sockets and consequently to impart a slight forward movement to the side marginal portions of the blank before the blank is finally clamped between the members 6 and 8. The pins 130 will preferably project from the surface of the member 6 a suitable distance with reference to the offsets 128 of the outer pins 126 to cause the forward movement of the side marginal portions of the blank to take place after the lateral or gathering movement of the outer gripping devices has been substantially completed, so that the movement of the material caused by the depression of the pins 130 is the third and final successive gathering or adjusting movement imparted to the blank before the final clamping of the marginal portion thereof.

In the operation of the machine it will be understood that after the heel portion of the upper has been formed and while it is still retained in the forming mechanism the parts come to rest with the mechanism for operating upon the toe part in position to receive the toe end of the upper, and with the cams shown on Fig. 1 somewhat advanced from the positions indicated on said figure. The clamp member 8 at this time is in its uppermost position, and the jaws 108 hang downward from the jaws 106 in position to receive the marginal portion of the upper, which is now inserted between the jaws of the gripping devices with its edge in contact with the pins or gages 126. The machine is now started again in operation by depression of its actuating treadle. As the cam shafts 30 and 98 resume their rotation, the cam 36 first operates upon the roller 32 to depress the rod 20 and move the yoke 10 and the clamp member 8 downward toward its clamping position with respect to the member 6. As the clamp member 8 carries the grippers downward, the jaws 108 which pertain to those two grippers which are nearer the median line of the clamp member first encounter the offsets or cams 128 on the respective pins 126 and are closed

upwardly to grip the marginal portion of the material between said jaws and the respective jaws 106; and as the downward movement of the clamp member continues the offsets 128 cause these grippers to swing toward each other in opposition to the force of the spring 114 and gather or pucker the gripped material. During this gathering movement of the central grippers the jaws 108 of the outer gripping devices are being moved upwardly by contact with the respective cams 128 and are finally caused to grip the material at the time when the inner grippers reach the straight portions of their respective cams 128 and, therefore, cease their swinging or gathering movement. The outer grippers are now swung inward by their cams 128 and cause a further gathering in of the material with respect to that portion which has been gathered by the inner grippers.

After the outer grippers have reached the straight portions of their respective cams and have therefore ceased their gathering movement, the clamp member 8 arrives at a point to grip the side marginal portions of the blank between said member and the ends of the pins 130, and further downward movement serves to depress these pins and consequently to impart to the side marginal portions of the blank a slight forward gathering movement toward the outer grippers. This is the third and final adjusting or gathering movement imparted to the blank, and is followed by the clamping of the marginal portion of the blank and the pressing or molding of the flange thereon. In the clamping position of the clamp members the toothed portions of the jaws 108 will, as previously explained, project slightly above the face of the member 6 to assist, as will also the ends of the pins 130, in securely holding the blank margin.

After the member 8 has been moved to clamping position, the cam 36 serves to retain it in such position during the toe forming operation, with the spring 22 imparting the requisite clamping pressure. The rotation of the shaft 30 next brings the offset portion of the cam groove 52 in position to operate the roller 50 and raise the slide 48 and the toe former 40 sufficiently to bring the forward under edge of the former in a plane above the marginal edge of the clamp member 8. Rotation of the shaft 98 has now brought the offset portion of the cam groove 102 in position to operate upon the roller 100 and raise the slide 96. This serves to straighten the toggle 80, 82 and move the slide 56 forwardly, thereby imparting forward movement to the toe former to form a bulge of the toe over its flange and simultaneously a crease between the flange and the toe. To facilitate this forming operation the edge of the clamp member 130

8 is cut backwardly upon its upper side. Rotation of the shafts 30 and 98 now ceases automatically, and the parts of the mechanism are retained in the position to which they have been moved to permit the upper to set to shape while the upper of the other shoe of a pair is being operated upon in another part of the machine. When it is desired to remove the upper, a further actuation of the starting mechanism, it will be understood, causes the parts to return to their first position represented in Fig. 1.

It will be seen by referring to Fig. 3 that the gripping or gathering devices are arranged unsymmetrically with reference to the clamp members in order to effect the required movement of different portions of the unsymmetrical blank; and it will be understood that in the mechanism for forming the upper of a left shoe these devices will be arranged in reversed relation to the sides of the clamp members.

Although the invention has been disclosed as embodied in apparatus having the specific features of construction shown and described, it will be understood that the invention in its broader aspects is not thus limited in its application but that other embodiments are comprehended within the spirit and scope of the claims.

It should be understood also that in the use of the terms "grippers" and "gripping devices" in the claims it is not the intention, except where required by the context, to limit the invention to devices of the form shown comprising pairs of coöperating jaws but to comprehend a broad range of equivalent devices adapted to perform the required functions. The novel method herein disclosed is not claimed in this application but forms the subject-matter of a divisional application Serial No. 59,042, filed Nov. 1, 1915.

Having described the invention, what we claim as new and desire to secure by Letters Patent of the United States is:—

1. In apparatus of the class described, the combination with means for forming a toe from a toe blank, of means for effecting a relative movement of adjustment of different portions of the margin of the blank previous to the operation of the toe forming means.

2. In apparatus of the class described, the combination with means for forming a toe from a toe blank, of means for effecting a shaping and compensating relative movement of different portions of the margin of the blank before the blank is acted upon by the toe forming means.

3. In apparatus of the class described, the combination with means for forming a toe from a toe blank, of means for gathering in the marginal portion of the blank in the regions of the abruptly curved portions of

the toe before the end of the toe is formed by said toe forming means.

4. In apparatus of the class described, the combination with means for forming a toe from a toe blank, of means for relatively moving different portions of the blank at its edge substantially in the plane of the margin before the blank is acted upon by the toe forming means.

5. In apparatus of the class described, the combination with means for forming a toe from a toe blank, of means for forming an out-turned sole attaching flange upon said blank, and means for gathering in the material along the line of said flange previous to the operation of said flange forming means.

6. In apparatus of the class described, the combination with means for forming a toe from a toe blank, of clamping means arranged to hold positively the marginal portion of the blank during the operation of the toe forming means, and means for effecting a relative movement of adjustment of different portions of the margin of the blank before said margin is secured by the clamping means.

7. In apparatus of the class described, the combination with means for forming a toe from a toe blank, of means for engaging different portions of the blank about its edge and moving said portions forwardly from opposite sides of the blank different respective distances toward the toe end substantially in the direction of the curved contour of the blank to gather the material about said end of the blank before the blank is acted upon by the toe forming means.

8. In apparatus of the class described, the combination with means for clamping a toe blank along its outer edge, of a toe former movable transversely and then longitudinally of said clamping means, and means for gathering in portions at the margin of said blank at the toe end previous to the longitudinal movement of the toe former.

9. In apparatus of the class described, the combination with means for forming a toe from a toe blank, of means for imparting relative movements of adjustment successively to different portions of the margin of the blank.

10. In apparatus of the class described, the combination with means for forming a toe from a toe blank, of means for gathering in the marginal portion of the blank at the toe end and for subsequently moving the marginal portion at the sides of the blank forwardly toward the toe end to adjust the relative positions of different portions of the material of the blank.

11. In apparatus of the class described, the combination with toe forming means, of members arranged to engage the marginal portion of a toe blank at a plurality of

points about the edge of the blank to feed the material forwardly toward the toe end of the blank, and means for imparting feed-ing movements in succession to said mem-bers respectively which are located at points successively more remote from the toe end of the blank.

12. In apparatus of the class described, the combination with a toe former, of a plurality of pivoted grippers constructed and arranged to engage the marginal portion of a toe blank at different points and movable about their pivots to effect relative adjustment of different portions of the blank, and means for moving said grippers.

13. In apparatus of the class described, the combination with means for forming an out-turned sole attaching flange upon an upper blank, of a plurality of grippers ar-20 ranged to engage the flange portion of the forepart of the blank, said grippers being pivoted for movement of the flange engag-ing portions thereof forwardly and in-wardly toward the toe end of the blank.

25 14. In apparatus of the class described, the combination with means for forming a toe from a toe blank, of a plurality of pivoted grippers for engaging the marginal portion of the blank, said grippers being arranged to radiate outwardly from the blank, and means for swinging said grippers to effect relative adjustment of differ-ent portions of the material of the blank.

35 15. In apparatus of the class described, the combination with means for forming a toe from a toe blank, of a plurality of grippers for engaging the marginal portion of the blank, said grippers being arranged to radiate outwardly from the blank and piv-40 otted for swinging movement substantially in the plane of said margin, and means for swinging the blank engaging ends of said grippers in the direction of the toe end of the blank.

45 16. In apparatus of the class described, the combination with means for forming a toe from a toe blank, of a plurality of grippers arranged to engage the marginal portion of the blank, means for moving toward 50 each other the grippers which are located near the toe end of the blank, and means for subsequently moving forwardly toward the toe end of the blank the grippers which en-gage the material at points more remote from the toe end.

55 17. In apparatus for forming a toe from a toe blank, a plurality of grippers comprising jaws arranged to grip the marginal portion of the blank, and means for swinging said grippers in directions to gather in the material toward the toe end of the blank.

60 18. In apparatus of the class described, the combination with clamp members rela-tively movable to clamping position, of 65 means operated by the relative movement of

said members for engaging portions of the material to be clamped at the margin of said material and moving said portions in direc-tions transverse to the direction of said rela-tive movement of the clamp members.

70

19. In apparatus of the class described, the combination with means for forming a toe from a toe blank, of clamp members relatively movable to clamp the marginal portion of the blank and form an out-turned flange thereon, and means operated during said relative movement of the clamp mem bers to clamping position for moving dif-ferent portions of the margin of the blank substantially in the plane of the margin.

80

20. In apparatus for forming a toe from a toe blank, the combination with clamp mem bers relatively movable to clamp the marginal portion of the blank, of gripping jaws between the clamp members arranged to en-gage said marginal portion, means for clos-ing said jaws to grip the blank during the relative movement of the clamp members to clamping position, and means for subse-quentlly imparting lateral movement to said 90 gripping jaws.

85

21. In apparatus for forming a toe from a toe blank, the combination with clamp mem bers relatively movable to clamp the marginal portion of the blank, of grippers 95 arranged to engage said marginal portion of the blank, said grippers being pivoted for swinging movement in substantially parallel relation to the blank engaging faces of the clamp members, and means for effecting 100 said swinging movement of the grippers before the blank is finally clamped by the clamp members.

100

22. In apparatus for forming a toe from a toe blank, the combination with clamp mem bers relatively movable to clamp the marginal portion of the blank, of a plurality of grippers carried by one of said members and arranged to grip the marginal portion of the blank, and means for moving said 105 grippers in substantially parallel relation to the blank engaging faces of the clamp members during the relative movement of said members to clamping position.

110

23. In apparatus for forming a toe from a toe blank, the combination with clamp mem bers relatively movable to clamp the marginal portion of the blank, of a plural-115 ity of grippers carried by one of said mem bers and arranged to grip the marginal por-tion of the blank, said grippers being ar-ranged unsymmetrically upon said clamp member to engage relatively farther from the toe end that portion of the blank which is to be located at the outer side of the shoe, and means for moving said grippers in substantially parallel relation to the blank 120 engaging faces of the clamp members during the relative movement of said members to clamping position.

125

130

24. In apparatus of the class described, the combination with clamp members relatively movable to clamp the marginal portion of a blank, of devices for gripping said portion of the blank at separate points, and means for moving said devices respectively in different directions transverse to the direction of relative movement of said clamp members before the blank is clamped by said members.

25. In apparatus of the class described, the combination with clamp members relatively movable to clamp the marginal portion of a blank, of a plurality of devices for gripping said portion of the blank at separated points, and means for moving different gripping devices at different respective times during the movement of the clamp members and in directions transverse to the direction of relative movement of said clamp members.

26. In apparatus of the class described, the combination with clamp members relatively movable to clamp a piece of material, of gripping devices carried by one of said members and movable with respect thereto in substantially parallel relation to the clamping face of said member, said devices being arranged to grip the marginal portion of said material before it is clamped by said members, means for normally positioning said devices with respect to said carrying member, and means for moving said devices to shift the position of different portions of said material during the relative movement of said members to clamping position.

27. In apparatus of the class described, the combination with clamp members relatively movable to clamp a piece of material, of a plurality of gripping devices pivotally mounted upon the clamping side of one of said members and movable about axes extending transversely to the plane of the clamping face of said member, said devices being arranged to grip the marginal portion of said material at different points before it is clamped by said members, and means for swinging said gripping devices to shift the position of different portions of said material before the material is clamped by said members.

28. In apparatus of the class described, the combination with clamp members relatively movable to clamp a piece of material, of a plurality of gripping devices pivotally mounted upon the clamping side of one of said members and movable about axes extending transversely to the plane of the clamping face of said member, said devices being arranged to grip the marginal portion of said material at different points before it is clamped by said members, means for normally positioning said devices upon their carrying member, and means for swinging said gripping devices about their axes dur-

ing relative movement of said members to clamping position.

29. In apparatus of the class described, the combination with clamp members relatively movable to clamp a piece of material, of a plurality of gripping devices pivotally mounted upon the clamping side of one of said members and movable about axes extending transversely to the plane of the clamping face of said member, said devices being arranged to grip the marginal portion of said material at different points before it is clamped by said members, yielding means for normally positioning said devices with respect to their carrying member, and cam means for engaging and swinging said devices about their axes during movement of said members to clamping position.

30. In apparatus of the class described, the combination with clamp members relatively movable to clamp a piece of material, of a plurality of gripping devices pivotally mounted upon the clamping side of one of said members and movable about axes extending transversely to the plane of the clamping face of said member, said devices being arranged to grip the marginal portion of said material at different points before it is clamped by said members, yielding means for normally positioning said devices with respect to their carrying member, means for swinging said gripping devices in different directions respectively to shift the positions of different portions of said material before it is clamped by said members, and means for varying the extent of swinging movement of said devices.

31. In apparatus of the class described, the combination with clamp members relatively movable to clamp a piece of material, of a plurality of gripping devices pivotally mounted upon the clamping side of one of said members and movable about axes extending transversely to the plane of the clamping face of said member, said devices being arranged to grip the marginal portion of said material at different points before it is clamped by said members, yielding means for normally positioning said devices with respect to their carrying member, means for swinging said gripping devices in different directions respectively to shift the positions of different portions of said material before it is clamped by said members, and means for varying relatively the extent of movement of the different gripping devices.

32. In apparatus of the class described, the combination with clamp members relatively movable to clamp a piece of material, of a plurality of gripping devices mounted upon the clamping side of one of said members and movable in a plane substantially parallel to the plane of the clamping face of said member, said devices comprising normally open jaws arranged to grip the mar-

ginal portion of said material, means for closing said jaws upon the material during the relative movement of said members toward clamping position, and means for 5 moving said devices to shift the positions of different portions of said material before the material is clamped by said members.

33. In apparatus of the class described, the combination with clamp members relatively movable to clamp the marginal portion of a toe blank, of a plurality of gripping devices pivotally mounted upon the clamping side of one of said members and movable about axes extending transversely 10 to the plane of the clamping face of said member, said devices comprising normally open jaws arranged to grip the marginal portion of said blank, means for first closing those jaws which are nearer the toe end 15 of the blank and for subsequently closing those jaws which are located farther from the toe end, and means for imparting swinging movement to said first named jaws and subsequently to said last named jaws to 20 gather the material about the toe end of the blank before the material is clamped by 25 said members.

34. In apparatus of the class described, the combination with clamp members relatively movable to clamp a piece of material, 30 of a plurality of gripping devices pivotally mounted upon the clamping side of one of said members and movable about axes extending transversely to the plane of the 35 clamping face of said member, said devices comprising normally open jaws arranged to grip the marginal portion of said material, and cam means for engaging and closing said jaws upon the marginal portion of said 40 material and for swinging said devices about their axes during the relative movement of said members to clamping position.

35. In apparatus of the class described, the combination with clamp members relatively 45 movable to clamp a piece of material, of a plurality of gripping devices pivotally mounted upon the clamping side of one of said members and movable about axes extending transversely to the plane of the 50 clamping face of said member, said devices comprising normally open jaws arranged to grip the marginal portion of said material, and cams for engaging and closing said jaws upon the material and for swinging 55 said devices about their axes during the relative movement of said members to clamping position, said cams being arranged to operate first upon those jaws which are nearer the toe end of the blank and to operate 60 subsequently upon those jaws which are more remote from the toe end.

36. In apparatus of the class described, the combination with clamp members relatively 65 movable to clamp a piece of material, of a plurality of gripping devices pivotally

mounted upon the clamping side of one of said members and movable about axes extending transversely to the plane of the clamping face of said member, yielding means for normally positioning said devices 70 with respect to their carrying member, and cams for engaging and swinging said devices about their axes during relative movement of said members to clamping position, said cams being adjustable to different positions to vary the extent of movement of said devices. 75

37. In apparatus of the class described, the combination with clamp members relatively movable to clamp a piece of material, 80 of a plurality of gripping devices pivotally mounted upon the clamping side of one of said members and movable about axes extending transversely to the plane of the clamping face of said member, said devices 85 being arranged to grip the marginal portion of said material and comprising jaws one of which is pivotally mounted with respect to the other and movable by gravity to open position, means for closing said jaws upon the material, and means for swinging said gripping devices to shift the positions of different portions of said material before the material is clamped by said members. 90

38. In apparatus of the class described, 95 the combination with clamp members relatively movable to clamp a piece of material, of a plurality of gripping devices pivotally mounted upon the clamping side of one of said members and movable about axes extending transversely to the plane of the clamping face of said member, said devices being arranged to grip the marginal portion 100 of the material at different points before it is clamped by said members and comprising jaws arranged to be normally opened by gravity, upright pins on the other clamp member, and yielding means for holding the gripping devices normally against said pins, said pins being formed with cam surfaces 105 for engaging and closing the jaws and for imparting swinging movement thereto during the relative movement of the clamp members to clamping position. 110

39. In apparatus of the class described, 115 the combination with clamp members relatively movable to clamp a piece of material, of a plurality of gripping devices pivotally mounted upon the clamping side of one of said members and movable about axes extending transversely to the plane of the clamping face of said member, said devices being arranged to grip the marginal portion 120 of said material at different points before it is clamped by said members, and means for swinging said gripping devices to shift the positions of different portions of the material before the material is clamped by said members, the clamp member opposite to said gripping devices having recesses formed 125 130

therein to receive said devices when said members are in clamping position.

40. In apparatus of the class described, the combination with clamp members relatively movable to clamp a piece of material, of a plurality of gripping devices pivotally mounted upon the clamping side of one of said members and movable about axes extending transversely to the plane of the 10 clamping face of said member, said devices being arranged to grip the marginal portion of said material at different points before it is clamped by said members, and means for swinging said gripping devices to shift the 15 positions of different portions of the material before the material is clamped by said members, the clamp member opposite to said gripping devices having recesses formed therein of a depth to receive the lower jaws 20 of said devices, said lower jaws being formed with toothed material engaging faces to assist in finally clamping the material.

41. In apparatus of the class described, the combination with clamp members relatively movable to clamp a piece of material, 25 of material engaging devices projecting from the clamping face of one of said members and yieldingly movable in directions inclined to the face of said member during 30 relative movement of said members to clamping position.

42. In apparatus of the class described, the combination with clamp members relatively movable to clamp a piece of material, 35 of pins projecting from the clamping face of one of said members and yieldingly movable endwise in directions inclined to the face of said member, said pins having their projecting end surfaces substantially parallel to said clamping face and roughened for engagement with the material so as to impart lateral movement to portions of the material during movement of the clamp members to clamping position.

45. 43. In apparatus of the class described, clamp members relatively movable to clamp a piece of material, one of said members being formed with sockets extending inwardly,

from its clamping face in directions inclined to the plane of said face, pins movable endwise in said sockets and yielding means for projecting the ends of said pins normally beyond the plane of said face. 50

44. In apparatus of the class described, the combination with clamp members relatively movable to clamp the margin of a toe blank, of pins projecting endwise from the clamping face of one of said members at the sides of said member in directions inclined toward the rear portion of the other clamp 55 member, said pins being arranged to engage the blank and depressible endwise on the relative movement of said members to clamp position so as to move portions of the material at the sides of the blank toward the 60 front end of the blank before the margin is finally clamped by the clamp members.

45. In apparatus of the class described, the combination with clamp members relatively movable to clamp the margin of a toe 70 blank, of pins projecting endwise from the clamping face of one of said members at the sides thereof, and yieldingly movable endwise in directions inclined toward the front of the clamp so as to move the material at 75 the sides of the blank forwardly on relative movement of said members to clamping position, and, pivoted, gripping devices arranged to engage the front marginal portion of the blank and movable to gather in the 80 material at the end of the blank during said relative movement of the clamp members.

In testimony whereof we have signed our names to this specification in the presence of two subscribing witnesses.
